[57] CLAIM

The ornamental design for golf tee, as shown and described.

DESCRIPTION

FIG. 1 is a top plan view of my golf tee showing my new design;

FIG. 2 is a bottom plan view thereof;

FIG. 3 is a side elevational view thereof; and,

FIG. 4 is a top isometric view thereof.

The clear round flexible tubing overlies and is affixed to the cylindrical plug from which pointed post extends.
